UNITED STATES PATENT OFFICE.

JOHN MURPHY, OF ADAMS, MASSACHUSETTS, ASSIGNOR OF ONE-HALF TO
JAMES A. ALLEN, OF SAME PLACE.

SEPARATING-PLATE FOR WARP-BEAMERS.

SPECIFICATION forming part of Letters Patent No. 371,272, dated October 11, 1887.

Application filed December 15, 1886. Serial No. 221,644. (No model.)

To all whom it may concern:

Be it known that I, JOHN MURPHY, of Adams, in the county of Berkshire, State of Massachusetts, have invented certain new and useful Improvements in Separating-Plates for Warp-Beamers; and I do hereby declare the following to be a full, clear, and exact description of the same, reference being had to the accompanying drawings, forming a part of this specification, and to the figures and letters of reference marked thereon.

My invention has for its object to improve the construction of separators for warp-beaming machines; and it consists in a certain improved construction, which I will now proceed to describe.

The yarn as it comes from the reels to be applied to the loom-beam is passed first between a series of pins, so as to divide it into a number of strands, then through a wire ridge, dividing it into strands of about sixteen threads, then through a separator formed of a zinc or copper plate provided with from one to three thousand holes or perforations, (one for each thread,) then through a comparatively coarse neck, and onto the loom-beam, which is secured in bearings and rotated by suitable mechanism. The yarn as it is separated covers a large area, and the threads being under tension draw toward the center and tend to cut or wear the lower sides of those perforations above the center and the upper sides of those below the center, while several rows at the center are scarcely worn at all.

As the perforations are thus worn sharp edges and corners are formed, upon which the threads are cut and broken, thereby delaying the operation of beaming and necessitating the removal and replacing of the separator by a new one. These plates form a considerable item of expense in a large mill, and it is therefore the object of my invention to provide an improved separator in which the wearing-surfaces of the perforations are movable and removable, and can be changed when slightly worn, thus prolonging the life of the separator.

In the drawings, Figure 1 is a front, Fig. 3 a side, and Fig. 2 a rear, view of a portion of a separator constructed in accordance with my invention.

Similar letters of reference in the several figures indicate the same parts.

The letter A indicates a portion of a separator having a number of perforations, a, corresponding to the number of threads in the warp. Now, as the threads B come to this separator they run from a number of independent strands on one side to a broad sheet, so to speak, of threads on the side next the beam, and are drawn over the lower edges of the upper series of perforations, C, straight, or nearly so, through the central series, D, and over the upper edges of the lower series, E.

On the rearside of the plate A, I place a number of removable horizontal iron or steel wires, F, extending from side to side and held in position by means of wire loops f, soldered or otherwise secured to the back of the plate, as shown. These horizontal wires are about on a level with the lower sides of the perforations of the upper series, C, and the upper sides of the lower series, E, or, in other words, on the wearing sides, so that the threads will pass over them and thus take all the wear off the sides of the perforations.

As the wires become worn by the threads they can be turned partly or wholly around or moved longitudinally, so as to present a new surface, and when badly worn can be removed and new ones put in their places.

It will be observed that by employing my invention a single separator can be made to last for years, the wires being turned from time to time or replaced by new ones when necessary and at very little cost.

I claim as my invention—

1. The combination, with the perforated separating-plate, of the transverse rods or wires forming the bearing-surfaces for one or more perforations in the plate, said wires being supported at one or more points between the end supports, substantially as described.

2. The combination, with the perforated separating-plate, of the transverse rods or wires forming the bearing-surfaces for one or more perforations supported at one or more points intermediate the end supports, the wires above the center of the plate being located at the lower sides of the perforations, and those below the center being located at the upper

sides of the perforations, substantially as described.

3. The combination, with the perforated plate, of the rods or wires loosely supported at three or more points in their lengths, and forming the wearing-surfaces for one or more perforations in the plates, substantially as described.

4. The combination, with the perforated sep-

arating-plate of a warp-beamier, of a rod or wire forming the bearing-surface for one or more perforations, and the metal loops secured to said plate for supporting said wire or rod, substantially as described.

JOHN MURPHY.
